COOLING MEANS FOR AIR COOLED
INTERNAL COMBUSTION ENGINESEarle A. Ryder, West Hartford, Conn., assignor,
by mesne assignments, to United Aircraft Cor-
poration, a corporation of Delaware

Application March 21, 1935, Serial No. 12,182

11 Claims. (Cl. 123—171)

This invention relates to improvements in cooling means for air cooled, internal combustion engines and has particular reference to improvements in a sectional air pressure baffle placed 5 across the stream of cooling air to increase the velocity of the airstream in the vicinity of the heat transferring portions of the engine, as described in application of Albert L. MacClain, Serial No. 621,425 filed July 8, 1932. It is one of the 10 objects of the invention to provide a cooling means of the type indicated which is resiliently secured to the engine and which may be readily mounted on and dismounted from the engine. Other objects and advantages will appear as the 15 description proceeds.

In the accompanying drawing I have illustrated a suitable mechanical embodiment of the idea of the invention. The drawing, however, is for the purpose of illustration only and is not to be taken 20 as limiting the invention, the scope of which is to be measured entirely by the scope of the appended claims.

In the drawing, Figure 1 is an elevational view of a fragmentary portion of a radial type, air cooled, internal combustion engine showing the sections of the air pressure diaphragm in place and the means for supporting such sections on the engine structure. Figure 2 is a top plan view of a fragmentary portion of one of the diaphragm 25 sections or baffles showing in detail a quick detachable device for securing the section to the engine. Figure 3 is a sectional view on the line 3—3 of Figure 2. Figure 4 is a sectional view on the line 4—4 of Figure 2, and Figure 5 is a sectional view on the line 5—5 of Figure 1.

Referring to the drawing in detail, the numeral 40 indicates generally, the crankcase of an internal combustion engine upon which are supported a plurality of radially extending cylinders 42. The cylinders may be arranged in one or more rows, with the axes of all the cylinders in the same row lying in the same circumferential plane. Each cylinder comprises a barrel portion 45, a head portion 46, and a pair of valve rocker arm 47 boxes 48 and 49, the surface of the barrel and head portions of each cylinder being provided with heat transferring fins 50.

The engine is cooled in the well known manner, by means of a blast of air forced through the engine by the propeller or by the forward motion of the vehicle, such as an airplane, upon which the engine is mounted. In order to cause the volume 55 of cooling air flowing through the engine to flow along the cooling surface of the cylinders at the maximum velocity, the spaces between adjacent

cylinders and between the rocker arm boxes of each cylinder are closed off by means of diaphragm sections or baffles 22 and 24 respectively.

Each baffle comprises a domed member preferably formed of sheet metal and having its outer edge turned over or flanged as indicated at 25 in Figure 4 and to form, when the baffles are all assembled on the engine, a continuous circumferential flat ring 28 around the outer circumference of the engine. If desired the engine may be surrounded by a suitable streamlined cowling 29 which may be supported upon and enclose the ring formed by the flanged outer edges of the adjoining baffles. The cylinder head baffles 24 are secured to the engine by means of brackets 30 and 31 located, respectively, at opposite ends of the baffle, at the outer or circumferential edge thereof. These brackets extend inwardly, as clearly illustrated in Figure 1, and are preferably apertured at the inner ends and rigidly secured 20 to the exhaust and intake ports respectively of the engine cylinder by suitable means such as the bolts 33. Referring to Figure 3, it will be observed that the upper end of each of the brackets 30 and 31 is bent over to fit within the flanged 25 outer edge of the baffle 24. A spacer 34 is interposed between the inner surface of the baffle flange and the respective bracket, the bracket and spacer being secured to the baffle by suitable means such as a rivet 35. By means of the above 30 described bracket construction the small cylinder head baffles 24 are rigidly secured to the engine cylinders.

The larger intercylinder baffles 22 are each provided at the outer edge with a quick detachable 35 device comprising a spring catch which includes a pair of oppositely extending slideable latch members 37 and 38 mounted in channel members 39 and 40 secured to the under surface of the bent over outer edge or flange of the baffle by suitable 40 means, such as rivets 42. The latch members 37 and 38 are bent over at their inner ends as indicated at 44 and a coil compression spring 45 is inserted between the bent over inner ends of the latch members to force the latch members outwardly in opposite directions, the bent over ends 44 also serving as finger pieces by means of which the latch members may be retracted within the limits of the baffle member on which they are mounted. 50

Referring to Figure 2 it will be observed that the spacer members 34 are cut-out as indicated at 48 to form latch keepers for the latch members 37 and 38. The sides of the cut-out portion along the length of the ring 28 are tapered outwardly 55

and the outer ends of the latch members are also tapered to form a wedging fit in the respective openings 48.

- From the construction so far described, it will be observed that after the head baffles 24 have been rigidly secured to the engine by means of the bolts 33 extending through the inner ends of the brackets 30 and 31, the intercylinder baffles may be quickly and easily secured in place by moving 10 the latch members 37 and 38 in a direction to compress the spring 45, placing the baffle member 22 in such a position that the ends of the latch members will be opposite the latch keepers 48 provided on the baffles 24 and then releasing the latch 15 members 37 and 38 so that the spring 45 will force the outer ends of the latch members into the keepers. The tapered construction of the keepers and latch members will provide a tight connection between the baffles 24 and 22 and effectively prevent 20 any rattling or vibration or loosening of the baffles as the engine dimensions change due to changes in engine temperature.

As the intercylinder baffles 22 extend inwardly for the entire length of the cylinders, they are 25 relatively long and narrow and hence must necessarily be secured to the engine at their inner ends. In order to accomplish this I have provided on each baffle 22 suitable contact surfaces or chafing strips adapted to bear against portions of the 30 outer surfaces of the adjacent cylinders and have provided through the lower end of the baffle a reinforced aperture 55 particularly illustrated in Figure 5, a plate 56 having tapered ends is fitted against the surfaces of the cylinders on the side 35 opposite the baffle 22 and provided centrally thereof with a bolt 58 which, when the plate 56 is in position, extends through the aperture 55. The end of the bolt extending through the aperture is threaded and provided with a wing nut 60 which 40 bears against the surface of the baffle and forces the lower end of the baffle tightly against the adjacent surfaces of the cylinders.

By means of the construction described the intercylinder baffles 22 are rigidly secured to the engine by a quick detachable means at their outer ends and by a readily removable means at the inner ends so that the baffles may be quickly and easily secured to the engine or detached therefrom. The construction also renders it possible to dismount one cylinder from the engine without the necessity of removing any of the baffles other than those in direct contact with the cylinder to be dismounted.

While I have illustrated and described in detail a particular mechanical embodiment which my invention may take, it is to be understood that the invention is not limited to the embodiment so illustrated and described, but that such changes in the size, shape and arrangement of parts may be resorted to as come within the scope of the appended claims.

Having now described my invention so that others skilled in the art may clearly understand the same, what I desire to secure by Letters Patent is as follows:

1. In combination with an air-cooled internal combustion engine, a sectional air pressure diaphragm interposed across the stream of cooling air to said engine comprising two or more groups of air directing sections, and quick detachable means comprising spring pressed latch members for mounting the sections of at least one of said groups on said engine.

2. In combination with an air cooled internal 75 combustion engine having a plurality of cylinders

arranged in the same plane, a sectional air pressure diaphragm comprising a plurality of intercylinder baffles and a plurality of head baffles arranged in the plane of said cylinders, and quick detachable means comprising spring pressed latch members and fixed latch keepers for securing said intercylinder baffles to said engine.

3. In combination with an air cooled internal combustion engine, a sectional air pressure diaphragm comprising a plurality of cylinder head 10 baffles alternately disposed with a plurality of intercylinder baffles interposed across the stream of cooling air to said engine, means for rigidly securing said cylinder head baffles to said engine and quick detachable means for securing said intercylinder baffles to said cylinder head baffles.

4. In combination with an air cooled internal combustion engine, a sectional air pressure diaphragm interposed across the stream of cooling air to said engine, and quick detachable means 20 for mounting said sections on said engine comprising, apertured brackets for rigidly securing alternate baffles to said engine and spring pressed latch members on the intermediate baffles for detachably securing said intermediate baffles to said 25 alternate baffles.

5. In combination with an air cooled internal combustion engine, a sectional air pressure diaphragm comprising, a plurality of cylinder head 30 baffles alternately disposed with a plurality of intercylinder baffles interposed across the stream of cooling air, and quick detachable means for mounting said baffles on said engine, comprising, apertured brackets rigidly secured to said cylinder head baffles and detachably bolted to said engine, 35 and spring pressed latch members slidably mounted on each of said intercylinder baffles extending beyond the limits thereof, and latch keepers on said head baffles to receive the outer ends of said latch members.

6. In combination with an air-cooled internal combustion engine, a sectional air pressure diaphragm comprising a plurality of cylinder head 40 baffles alternately disposed with a plurality of intercylinder baffles interposed across the stream of cooling air, means for resiliently securing said baffles together and to said engine comprising, brackets secured to said cylinder head baffles and to said engine, latch keepers on said brackets, a pair of oppositely disposed latch members on 50 each of said intercylinder baffles engageable in said keepers, a compression spring between the latch members of each pair, and readily removable means for securing the inner end of each intercylinder baffle to said engine.

7. In combination with an air cooled, internal combustion engine having a plurality of spaced apart cylinders, a sectional air pressure diaphragm comprising a plurality of cylinder head 55 baffles alternately arranged with a plurality of intercylinder baffles disposed across the stream of cooling air to said engine, and means for mounting said diaphragm on said engine comprising, bracket members for securing said cylinder head baffles to said engine cylinders, latch 60 keepers on said brackets, slidably mounted latch members on said intercylinder baffles, and springs carried by said intercylinder baffles for forcing said latch members into resilient engagement in said latch keepers, said baffles being flanged 65 transversely at their outer edges to provide a continuous, flexibly interconnected strip along the outer dimensions of said engine cylinders.

8. In combination with a radial, air cooled internal combustion engine having a plurality of 75

spaced apart cylinders, a sectional air pressure diaphragm comprising a plurality of cylinder head baffles alternately arranged with a plurality of intercylinder baffles disposed across the stream 5 of cooling air to said engine, and means for mounting said diaphragm on said engine comprising, bracket members on said cylinder head baffles secured to said engine cylinders, latch keepers on said brackets, slidably mounted latch 10 members on said intercylinder baffles, and springs carried by said intercylinder baffles for forcing said latch members into resilient engagement in said latch keepers, said baffles being curved longitudinally and flanged transversely at their 15 outer edges to provide a continuous, flexibly interconnected ring around the outer circumference of said engine.

9. In combination with a radial air cooled internal combustion engine having a plurality of spaced apart cylinders, a sectional air pressure diaphragm comprising a plurality of cylinder head baffles alternately arranged with a plurality of intercylinder baffles disposed across the stream of cooling air to said engine to deflect 20 said air to the surfaces of said cylinders, and means for resiliently securing said baffles to- 25

gether and mounting them on said engine, said baffles being curved longitudinally and flanged transversely at their outer edges to provide a continuous flexibly interconnected ring around the outer circumference of said engine. 5

10. In combination with an internal combustion engine having a plurality of radially disposed cylinders and a plurality of air baffles disposed between and around said cylinders to restrict the flow of air through said engine, quick 10 detachable means comprising finger releasable spring pressed latch members independently securing individual baffles to the cylinders of said engine.

11. In combination with an internal combustion engine having a plurality of radially disposed cylinders, a cowl surrounding said engine, and a plurality of air baffles disposed between adjacent engine cylinders and closing the spaces between said engine and said cowl, means connecting said engine, said baffles, and said cowl, said means including quick detachable spring pressed connecting means for attaching individual baffles to said engine. 15 20
